UNITED STATES PATENT OFFICE.

ERNEST WINDSOR BOWEN, OF SURREY, ENGLAND, ASSIGNOR OF THIRTY-FIVE PER CENT. TO THOMAS LEWIS DAVIES, OF LONDON, ENGLAND.

PROPELLER FOR OPERATION IN AIR.

1,331,612.

Specification of Letters Patent. Patented Feb. 24, 1920.

Application filed August 12, 1919. Serial No. 317,053.

To all whom it may concern:

Be it known that I, ERNEST WINDSOR BOWEN, a subject of the King of England, residing in Surrey, England, have invented certain new and useful Improvements in Propellers for Operation in Air, of which the following is a specification.

This invention relates to propellers for operation in air, and is particularly applicable to propellers for aeroplanes.

Wooden air-screws as now used deteriorate somewhat rapidly and whipping of the blade occurs when driving, which sometimes results in fracture at the root; with 15 a blade broken off, the machine driven by it becomes unmanageable.

A primary object of this invention is to provide an air-screw to which these defects are not attached, and which for a given 20 weight shall be mechanically stronger than those at present in use, and shall retain its true form and pitch under full load conditions.

Another object is to provide an air-screw 25 blade consisting solely of a cellular metal structure, and a further object is to enable an air-screw blade to be built up by welding together a number of steel pressings.

A still further object is to facilitate the 30 construction of blades comprising a cellular metal structure by bending the edges of the longitudinal driving members thereof to correspond to the shape of the two operative faces of the blade, so that when these 35 members are connected together either directly, say by welding, or indirectly, say by means of sheet-metal or wood secured to them, a blade of the required contour shall be readily obtained.

40 Previous constructions of air-screws have been proposed wherein a plurality of ribs were used which extended longitudinally through each blade, each rib being secured, along its two lateral edges, to outer members, which members constituted the driving 45 faces of the blade, and wherein a number of ribs were disposed transversely across the blade; another construction employed in each blade was a single longitudinal strengthening rib whose root was welded to the boss and situated in a plane 50 passing through or approximately through the axis of the said boss.

The present invention consists in the construction, arrangement and combination of

parts described hereinafter and pointed out in the claims.

One embodiment of the invention and several modifications thereof are diagrammatically illustrated by way of example in 60 the accompanying drawings wherein—

Figure 1 is an elevation showing an air-screw according to the invention, part of one blade being shown broken away,

Fig. 1^a is a detail plan view of the boss of 65 the propeller whereon are welded driving arms shown broken away, and

Fig. 2 comprises cross-sections *a*, *b*, *c*, *d*, *e* and *f* taken, respectively, on the lines lettered correspondingly in Fig. 1;

Fig. 3 is a detail cross-sectional view 70 showing a modified form of driving arm of in air-screw blade according to the invention;

Fig. 4 is a cross-section of a modified 75 form of blade according to the invention;

Fig. 5 is a detail view showing another form of driving arm;

Fig. 6 is an elevation showing part of an 80 air-screw according to the invention comprising reinforced wooden blades, and

Fig. 7 comprises cross-sections *g*, *h*, *i*, *k* and *l* taken, respectively, on the lines lettered correspondingly in Fig. 6.

Like reference letters designate corresponding parts in all the views.

Referring first to Figs. 1, 1^a and 2, a boss A of a propeller is constituted by a flanged steel sleeve having its axis of rotation at A¹. Each blade comprises three driving-arms B 90 that are welded at one end to the boss A and extend outward approximately parallel to one another to the tip of the blade. The two lateral edges of each of these driving-arms B are turned one in one direction, and the other in the opposite direction to constitute flanges B¹, B² shaped each in conformity with the required exterior contour of the parts of the blade at which they are situated.

A steel plate C shaped to form the one operative driving face of the blade is welded to the flanges B¹ and to one of the flanges A² on the ends of the boss A, and a second steel plate C¹ shaped to form the 105 other operative driving face of the blade is welded to the flanges B² and to the other flange on the boss A. The edges of these two shell plates C, C¹ met all around the blade except where they embrace the boss 110

and are secured together by welding along the leading edge, and along the trailing edge of the blade, as indicated in Fig. 2 at C² and C³, and also at the tip of the blade. If desired, these plates and also the driving-arms may diminish in thickness from the root to the tip of the blade. The joints at the edges of the plates may be butt or lap welded; if they are lap welded the two edges of the plates are preferably each reduced in thickness before being welded so as to provide a smooth joint.

The driving arms have their roots disposed each in a plane transverse to the axis 15 of the boss as clearly shown in Fig. 1^a, and are then twisted more and more out of these planes the nearer they approach to the tip of the blade as will be understood from Figs. 1 and 2. Also, as clearly shown in 20 these figures, each driving arm is widest near the boss and becomes gradually narrower toward the tip of the blade.

Preferably, two blades on opposite sides of the boss are made integral one with the 25 other. In this case, two corresponding driving arms, one for each blade are made by pressing them in one piece of the required shape out of sheet steel, a hole being formed between the two arms in the middle of the 30 pressing whereupon, the two arms integral one with the other are threaded on to the boss and welded thereon. Any desired number of driving arms B for two opposite blades may be provided at any convenient 35 distance apart in this manner. The steel plates C for the two blades are likewise made integral one with the other, as also are the plates C¹, and these plates each extending from tip to tip of the blades are 40 welded one to the other at their edges and to the boss, as described above with reference to Figs. 1 and 2.

It will be seen that each blade made as described above is of similar structure and 45 of great strength for a given weight. Such a blade is adapted to retain its true form and pitch under full load conditions, and will also largely absorb vibration without resultant fatigue and without consequent 50 permanent deformation.

As shown in Fig. 3, the web of the driving arm B³ is corrugated, whereby the arm is rendered stiffer longitudinally than a similar arm having a flat web.

55 An air-screw according to the invention whereof each blade comprises sheet metal driving-arms may be built up without using separate shell plates as described above shaped to the exterior contour of the blade 60 and mounted on the driving arms, but by welding the flanges of one driving-arm directly to those of the next, welding together the two flanges to one outer driving-arm at the leading or trailing edge of the blade, 65 and shaping the other outer driving-arm to

the required form of the other operative edge of the blade. As shown in Fig. 4, the driving-members B⁴ are of U section, and the flanges B⁵, B⁶ of all the arms except one bear upon shoulders formed on the flanges of 70 the next arm and are welded thereto, so that smooth exterior or propelling faces are provided. The two flanges B⁵, B⁶ of the one outermost arm shown at the left hand of Fig. 4 are welded together at their lateral 75 edges to form the trailing edge of the blade, while the other outermost arm shown at the right hand of the figure is shaped to constitute the leading edge and is not provided with the above-mentioned shoulders. At the 80 root of the blade these driving arms may be nested more completely one into another than is shown in the figure, and threaded on to a sleeve forming the boss, as described above, the whole being welded into a continuous, light and rigid cellular structure. 85

Fig. 5 is a perspective view showing a driving-arm B⁷ having castellated flanges some parts of which are turned in one direction and alternate parts in opposite directions. This form of driving-arm may be employed in a manner similar to that described above in reference to Figs. 1, 1^a and 2. 90

Referring to Figs. 6 and 7, the boss A has a hollow radial arm A³ into which is socketed the root of a wooden blade reinforced with metal driving-arms B of the kind described above with reference to Figs. 1, 1^a and 2. In this blade the driving-arms B are welded in the arm A³; their flanges do not 95 carry shell plates C, C¹ along their entire length, however, but only at the root end of the blade. The root of the blade is thus a tubular structure whereof two plates C, C¹ constitute the periphery of the desired 100 exterior shape, and wherein are fixed pieces of timber D which extend to the tip of the blade. The pieces of wood D are shaped each to the required exterior contour of the portion of the blade which they form, and the flanges or the turned edges of the driving-arms D at the air-propelling faces of 105 the blade are let into the pieces of wood D so that the outer face of each flange is flush with the adjacent faces of the pieces of 110 wood D. Pegs E are used in the usual manner for securing together the pieces of wood D and the driving-arms B. 115

One advantage of the mode of constructing wooden blades as described above with 120 reference to Figs. 6 and 7 is that it enables much shorter pieces of timber to be used than those required heretofore for building propellers of a corresponding size. Consequently considerable economy of material is 125 effected.

It will be appreciated that each cell or compartment of the metallic structure constituting a blade as described above may vary in size from the root to the tip of 130

the blade, and that the driving-arms in one blade need not be quite parallel to one another along their entire length.

What I claim as my invention and desire to secure by Letters Patent is:—

1. In an air-screw, the combination with a metal boss, of a blade carried thereby, which blade comprises a plurality of metal driving-arms that are disposed approximately parallel to one another with their edges shaped to conform to the two operative faces of the blade, are fixed to the boss, extend therefrom toward the tip of the blade, and have their roots disposed in planes transverse to the axis of the boss and spaced relatively to one another along the boss in the axial direction thereof.
2. In an air-screw, the combination with a metal boss, of a blade carried thereby, which blade comprises a plurality of metal driving-arms that are disposed approximately parallel to one another with their edges shaped to conform to the two operative faces of the blade, are fixed to the boss, extend therefrom toward the tip of the blade, and have their roots disposed in planes transverse to the axis of the boss and spaced relatively to one another along the boss in the axial direction thereof, and means shaped to the required exterior contour of the blade carried by the driving-arms.
3. In an air-screw, the combination with a metal boss, of a blade carried thereby, which blade comprises a plurality of metal driving-arms that are disposed approximately parallel to one another with their edges turned over to conform to the required exterior contour of the blade, are fixed to the boss, extend therefrom toward the tip of the blade, and have their roots disposed in planes transverse to the axis of the boss and spaced relatively to one another along the boss in the axial direction thereof, and sheet-metal shaped to the required exterior contour of the blade rigidly secured to the edges of the driving-arms.
4. In an air-screw, the combination with a metal boss, of a blade carried thereby, which blade comprises a plurality of metal driving-arms that are disposed approximately parallel to one another with both their longitudinal edges shaped to conform to the two operative faces of the blade, are fixed to the boss, extend therefrom toward the tip of the blade, and have their roots disposed in planes transverse to the axis of

the boss and spaced relatively to one another along the boss in the axial direction thereof, and two sheet-metal plates shaped each to 60 conform to an operative face of the blade and rigidly secured to the said edges of the driving-arms on opposite sides of the latter and welded together at their abutting edges.

5. In an air-screw, the combination with 65 a metal boss, of two blades carried thereby, which blades comprise a plurality of metal driving-arms that are disposed approximately parallel to one another with their edges shaped to conform to the two operative faces of the two blades, are threaded on and secured to the boss, extend therefrom toward the tip of each blade, and have their roots disposed in planes transverse to the axis of the boss and spaced relatively to 70 one another along the boss in the axial direction thereof.

6. An air-screw blade having a cellular metal structure which comprises a plurality of metal driving-arms that are disposed approximately parallel to one another with their edges turned to conform to the two operative faces of the blade, extend from the root toward the tip of the blade, and have their roots disposed in planes transverse to the axis of rotation of the blade and spaced relatively to one another along the 80 said axis.

7. An air-screw blade having a cellular metal structure which comprises a plurality 90 of metal driving-arms that are disposed approximately parallel to one another with their edges turned to conform to the two operative faces of the blade, extend from the root toward the tip of the blade, and have 95 their roots disposed in planes transverse to the axis of rotation of the blade and spaced relatively to one another along the said axis and sheet-metal shaped to the required exterior contour of the blade rigidly secured to the 100 shaped edges of the driving-arms

8. An air-screw blade having a cellular metal structure which comprises a plurality of corrugated metal driving-arms that are disposed approximately parallel to one another with their edges turned to conform to the two operative faces of the blade, extend from the root toward the tip of the blade, and have their roots disposed in planes transverse to the axis of rotation of the 110 blade and spaced relatively to one another along the said axis.

In testimony whereof I affix my signature.
ERNEST WINDSOR BOWEN.
